UNITED STATES PATENT OFFICE.

ARTHUR ATWATER KENT, OF ARDMORE, PENNSYLVANIA.

DESIGN FOR AN IGNITION-DISTRIBUTER.

56,748.

Specification for Design. Patented Dec. 14, 1920.

Application filed May 22, 1920. Serial No. 383,573. Term of patent 14 years.

To all whom it may concern:

Be it known that I, ARTHUR ATWATER KENT, a citizen of the United States, residing at Ardmore, county of Montgomery, State of Pennsylvania, have invented a new, original, and ornamental Design for an Ignition-Distributer, of which the following is a specification, reference being had to the accompanying drawing, forming part hereof.

Figs. 2 and 3 are plan and end views, respectively, of the same.

I claim:

The ornamental design for an ignition distributer, as shown.

In testimony whereof I have hereunto affixed my signature this 20th day of May, 1920.

ARTHUR ATWATER KENT.
